MOUNTING MEANS FOR THE WARP STOP MOTION DEVICE IN WEAVING LOOMS

Jaime Picanol, Zillebeke-lez-Ypres, Belgium

Application November 1, 1956, Serial No. 619,785

Claims priority, application Belgium December 17, 1955

1 Claim. (Cl. 139—369)

As it is well known, in weaving, the exact positioning of the toothed racks and the warp stop motion device is of great importance. Indeed, if for instance the toothed racks are too high there will be excessive friction between the threads and the warp stop motion, and inasmuch the loom, when stopped, is not arrested with sufficient promptitude, the tag or lamella will have difficulty in dropping, whereby a fault will be produced in the fabric whenever the loom stops. If, on the other hand, the racks are positioned too low, the threads will rub against the bottom side of said racks, which is equally harmful. It follows then, that the grain or, with other words, the appearance of the fabric depends very much on the correct positioning of the toothed racks and the warp stop motion. It is therefore of great importance to provide means for rapidly and accurately shifting or adjusting the warp stop motion device, whereby the latter may readily be lifted or lowered, preferably even during the operation of the loom.

The object of the invention is to provide such means. For this purpose the warp stop motion is mounted on two pivoting arms disposed at either side of the loom, so that in order to lift or to lower said warp stop motion it suffices to unscrew both said arms and to swing them upward or downward so as to almost instantaneously effectuate the required positional adjustment of said warp stop motion device. Said operations may readily be executed, while the loom is running. This in fact is very important, as it enables to observe whether the crossing of the threads is taking place correctly and thus to choose the right position under actual operating conditions, whereby the adjustment is greatly facilitated. Moreover, by judiciously choosing a suitable location for the pivoting center of said supporting arms, e. g. near the lower limit of the travel of the heddle frames whereby the sheet of warp threads is guided, it may be obtained, that by lifting or lowering the warp stop motion device the latter will readily be placed and maintained in parallel relationship with the sheet of threads. As a result the warp stop motion device may be made to faithfully follow, in a way, the movements of the sheet of threads, which is of great importance for the conduct of the weaving operation. In fact, the arrangement of the invention enables to maintain a constant relative position between the warp stop motion device and the sheet of warp threads, this constant relative position being ensured all through the weaving operation, whichever position is taken up by the sheet of threads, with other words by the back rest, and said constant relative position may be set and adjusted even while the loom is continuing its normal operation. This arrangement according to the invention may be realized in different constructional forms, as various forms and relative positions may be resorted to as regards the supporting arms of the warp stop motion device as well as the means provided for duly adjusting the position of said arms, while the loom is at rest or in operation.

2

The various characteristic features of the invention will be brought out more clearly in the following description of an embodiment, which will be given with reference to the appended drawings, wherein:

5 Figure 1 is a side elevational view of the essential elements of a loom, letting appear the location of the improved mounting of the warp stop motion device, which is the subject of the invention;

10 Figures 2 and 3 diagrammatically and very succinctly show the essential elements of the improved mounting of the warp stop motion according to the invention;

Figure 4 is a diagrammatic view intended to illustrate the favorable results obtained by means of the improved arrangement according to the invention;

15 Figure 5 represents a front view of a practical embodiment of the improved arrangement according to the invention.

Referring now to the schematic representation of Figures 2 and 3, the warp stop motion device given,

20 in outline, by 1 is mounted on the ends of two arms 2 disposed at either side of said warp stop motion, each of said arms being mounted on a pivot such as 3 fixed on the loom frame. Said arms 2 may be swung, adjusted and secured in any wanted angular position, e. g.

25 with the aid of a set screw 4 resting on a stud mounted on a fixed part of said loom, said stud being engaged in an arcuate elongated slot 6 contrived in a widened portion of said arms 2. By screwing down or up said screw 4, said arms 2 may be swung upwards or downwards about their respective pivots 3, lifting or lowering the warp stop motion 1, as they are so swung. The pivots 3 are located e. g. relatively to the lower limit of the motion of the heddle frames whereby the sheet of threads (not shown) is guided, so as to cause the

30 warp stop motion device, while being lifted or lowered on said arms, to maintain at least approximately a parallel relation with respect to the sheet of threads, as the slope of the latter is changed due to the rising and falling movements performed by the back rest during the weaving.

For this purpose said pivots 3 are preferably disposed at a level adjacent the lower limit of the heddle frame movement. Preferably also, the warp stop motion device is so mounted as to permit adjustment of its angular relationship with respect to the arms 2. For this purpose it may be mounted, e. g. so as to swing on pivots 7 engaged in an elongated slot 8 formed in said arms, its angular position being determined, on the one hand, by a pin 9 passing through said elongated slot 8 and at the same time through a curved oblong opening 10 in the warp stop motion device and, on the other hand, by a set screw 11 passing through a threaded hole of an ear 12 integral with said warp stop motion device, said set screw having its end resting on the arm 2. By screwing in or out said screws 11 the warp stop motion device may be made to swing upwards or downwards respectively on the pivots 7. At the same time the warp stop motion device may be made to slide a short distance on said arms 2, in a manner related with said swinging motion. By the joint action of said different means the position of the warp stop motion device may thus be adjusted with great accuracy in accordance with the position of the sheet of warp threads.

65 In Figure 4, the relative position of the warp stop motion device and the sheet of threads have been shown somewhat diagrammatically. In Figure 5, the essential elements have been shown of a practical embodiment, comprising the warp stop motion device 1 which may be of any type, supporting arms such as 2, the pivots such as 3, on which said arms may swing, set screws such as 4 and the fixedly mounted studs 5 each engaged in an arcuate slot 6.

70

In this practical embodiment the warp stop motion device 1 is mounted at either side on a pivot 7 engaged in an elongated slot formed in said arm 2. Said warp stop motion device is also supported on each of said arms 2, on the one hand by a pin engaged in said elongated slot 8 as well as in the curved oblong opening 10, and on the other hand with the aid of a screw 11 going through a threaded hole in a projecting part 12 of said warp motion device.

The embodiment described is exceedingly simple and permits a very accurate, highly stable adjustment of the position of the warp stop motion device with a view to maintaining the latter at least approximately in a parallel relationship with respect to the sheet of warp threads.

The means for swinging, adjusting and securing the arms 2 with the warp stop motion device 1 may obviously be subject to multiple variations and modifications, as well as the shape and dimensions of said arms and the accessory parts pertaining thereto.

What I claim is:

In weaving looms having a warp stop motion device, supporting arms mounting said warp stop motion device,

said arms being pivotally mounted, at one of their ends, on pivots fixed on said loom, said arms each having a longitudinally elongated slot formed at the other of its ends and having a transversely elongated arcuate slot intermediate between said pivot and said longitudinal slot, a pin simultaneously engaged in said longitudinal slot and in a curved oblong opening in said warp stop motion device, a pair of studs fixedly mounted on said loom and each engaged in said transverse slot of one of said arms, a set screw for each of said arms, extending transversely through part of said arm and into said transverse slot and having its free end resting on said stud in said slot.
